UNITED STATES PATENT OFFICE.

JOHN W. WATKINS, OF PHILADELPHIA, PENNSYLVANIA.

AUTOMATIC FIREPROOF WINDOW.

SPECIFICATION forming part of Letters Patent No. 778,927, dated January 3, 1905.

Application filed September 10, 1903. Serial No. 172,566.

To all whom it may concern:

Be it known that I, JOHN W. WATKINS, a citizen of the United States, residing at No. 2223 East York street, in the city of Philadelphia and State of Pennsylvania, have invented certain new and useful Improvements in Automatic Fireproof Windows, of which the following is a specification, reference being had to the accompanying drawings.

10 My invention relates to a fireproof window composed entirely of non-combustible material.

My invention comprises, among other things, a window-frame which is entirely constructed of sheet metal by the infolding and interlocking of component parts. It also comprises the sashes similarly constructed; also, means whereby the sashes may be removed from the frame without disconnection of the 15 component parts of either the sash or the frame. Means are likewise provided whereby the sashes are made capable of being swung, as upon a horizontal pivot, in such way as to give access to the outer surfaces for cleaning 20 or for other purposes. Finally, means are provided whereby when the temperature of the room in which the window is set rises to an abnormal point both sashes, if open, automatically close themselves.

30 In the accompanying drawings, Figure I is a front elevation of a window embodying my invention. Fig. II is a central transverse vertical section of said window, having the central portion broken away for convenience of illustration. Fig. III is a fragmentary rear elevation of the upper corner of the window-frame. Fig. IV is a fragmentary front elevation of the same. Fig. V is a horizontal transverse section of one of the jambs. Fig. 35 VI is a fragmentary plan view taken above one of the jambs. Fig. VII is a fragmentary inverted plan view of the same. Fig. VIII is a fragmentary elevation of the rear lower corner of the window-frame. Fig. IX is an elevation 40 of the front lower corner of the same. Fig. X is a fragmentary edge view of one of the top corners. Fig. XI is an edge elevation of the lower sash, the central portion being broken away for convenience of illustration. Fig. XII is a fragmentary elevation of the 45

front upper corner of said sash. Fig. XIII is a fragmentary elevation of the rear upper corner of the same. Fig. XIV is a horizontal transverse section, taken on line XIV XIV in Fig. XVI, of the stile of the sash, showing 55 the movable member, which is shown extended. Fig. XV is a sectional view similar to Fig. XIV, taken on line XV XV in Fig. XVII, showing the movable member retracted. Fig. XVI is a side elevation of that portion of the 60 stile shown in Fig. XIV. Fig. XVII is a vertical section taken on the line XVII XVII in Fig. XV. Fig. XVIII is a fragmentary inverted plan view of the corner of said sash. Fig. XIX is a vertical transverse sectional 65 view of the meeting-rails. Fig. XX is a fragmentary elevation of the front lower corner of the sash. Fig. XXI is a fragmentary elevation of the rear lower corner of the sash. Fig. XXII is a vertical sectional view of said 70 sash, taken on the line XXII XXII in Fig. XXIV, showing the automatic closing device. Fig. XXIII is a central vertical section of the same, taken on the line XXIII XXIII in Fig. XXII. Fig. XXIV is a horizontal transverse 75 section taken on the line XXIV XXIV in Fig. XXIII. Fig. XXV is a modified construction of the automatic closing device. Fig. XXVI is a horizontal transverse section 80 of said modified form, taken on the line XXVI XXVI in Fig. XXV.

I will describe my invention by taking up the several branches of it as already enumerated in order.

The frame construction.—According to my 85 invention, the window-frame is composed entirely of sheet metal, preferably galvanized iron, and is built up by the infolding and interlocking of parts without the use of solder or riveting or any other elements of construction which are liable to be destroyed by intense heat. In order to understand the construction of the frame, reference must be had to Figs. I to X, inclusive, of the drawings, and it may here be remarked that they are 90 unusually full in detail, because the method of infolding and interlocking the parts is a matter which can be much more readily shown in drawings than described. For this reason it will only be necessary for me to refer briefly 95 100

to the parts by the combination of which the frame is made up. The head of the frame is composed mainly of the piece A, folded so as to form the moldings, the seat for the top 5 sash, and the front and back wall, as will be best understood by reference to the cross-section of this piece shown in Fig. II. The upper ends of piece A are united by a flat piece A', which forms the top of the head, inter-folded at its edges with the front and back edges of piece A, as seen in Fig. II. Each jamb is composed chiefly of piece B, which is bent and folded, as seen in Fig. V, so as to form both the outside and front and back of 10 the jamb, including the moldings. The face of the jamb—that is to say, the portion which faces the sashes—is formed of piece B', which is folded so as to form the front and back runways for the sashes and is interfolded at 15 its edges, as shown, with the edges of piece B. The interfold occurs near the edge of the exposed facing of the jamb, and by inserting it between the moldings and the runways it serves to stiffen the latter. Piece B is formed 20 with a parting-bead in the shape of a very deep central infold b^{10} , which is useful both as a brace strengthening the jamb and as a means for affording attachment between the frame and the building in which the window is to be 25 set. It also serves to divide the jamb into two separate compartments for the sash-weights, thus avoiding the possibility of interference between them. The inner end of this infold b^{10} is fastened centrally to the piece B' by a 30 series of screws b^{11} , which at convenient intervals are inserted into nuts b^{12} , set in the infold. This infold terminates at either end when it reaches the plane of the lower edge of the head and the top edge of the sill, the 35 folding of the cut edges of the piece B whereby this termination is effected being shown in Fig. X. Piece B is interlocked with piece A by means of a series of flaps $b b' b'' b''' b'''' b''''' b'''''' b'''''''$, each of which projects through a corresponding slot cut in piece A and is turned over at the top, so as to hold the two pieces together. The sill is composed of the piece C, which is folded, as best seen in Fig. II, so as to form both the front and back and top of 40 the sill. Piece B interlocks with piece C by a series of flaps $b^{12} b^{13} b^{14} b^{15} b^{16} b^{17} b^{18} b^{19} b^{20}$, which are similarly thrust through corresponding slots in piece C and turned over, so as to unite the pieces together. 45

50 The folding and cutting of the pieces B and C so as to effect the formation of the corners appears in Figs. VIII and IX, it being noted that that portion of piece B which forms the front molding is cut so as to continue down on the outside of piece C, at the same time allowing the turned-up edge of piece C to pass behind it, as indicated at c' in Fig. IX.

As thus described the entire frame is composed by the proper interfolding and inter-

locking of the seven pieces A, A', B, (two) B', 65 (two) and C.

It will be noted that the piece B' is not united to either the head or sill at the top or bottom. It is held in place solely by means of the interfold along its edges and the screw b^{11} . By 70 reason of the exposed position of this interfold (not in contact with the structure in which the frame is set) it is possible by loosening the screws b^{11} to withdraw piece B' altogether, thus securing access to the weight- 75 compartments for purposes of repair.

Sash construction.—As usual, the top sash runs in the outermost of the two runways. It has attached to it (by the cross-bars to be hereinafter described) two flexible chains, which 80 run over pulleys set in the pieces B' B' near their top and carry the sash-weights in the usual manner. The weights, however, do not merely balance the sash, as is usually the case, but considerably overweight it, so that the 85 sash ascends of its own accord, provided it is not positively held in any lower position in which it may be set. The bottom sash is hung by means of similar cords and weights; but the latter considerably underweight it, so that 90 it descends to the bottom of its runway unless it is positively held in any raised position in which it may be set.

I will first describe the bottom sash, 95 promising that in nearly all points the two sashes are similar. The bottom sash is shown in Figs. XI to XXI, inclusive, and also in partial section in Fig. II. The top cross-piece or meeting-rail of this sash is composed of the three pieces D, D', and D'', which are 100 interfolded, as seen most clearly in Fig. XIX. The top or cover piece D'' is prolonged outwardly and bent so as to form a flap which when both sashes are closed interlocks with a corresponding flap formed on the lower inner corner of the meeting-rail of the top sash, so as to produce a very tight joint across the 105 center of the window. The vertical side pieces or stiles of the sash are composed mainly of the piece E, (see Figs. XIV and XV,) which 110 is so folded as to form both front and back and inner edge, including the moldings and groove for the glass, which latter is marked e. The remainder of each stile—namely, the edge which slides in the runway—is formed of a movable or telescopic piece E', folded as 115 seen in Figs. XIV and XV, its side edges being received into corresponding slots formed by the doubling of the edges of piece E. When these two pieces are pushed together 120 or collapsed, as shown in Fig. XV, the sides of the sash are free from the runway; but when piece E' is protruded, as shown in Fig. XIV, it snugly engages the runway, and the sash cannot be removed from the frame. 125 The telescopic motion of piece E' in relation to piece E is effected and controlled by toggle-joints distributed within the stiles at con-

venient vertical distances. In a sash of ordinary size two may be employed. Each of these toggle-joints consists of two links f, f' , pivoted together. The projecting end of piece 5 f is pivoted to the piece E' , as seen in Fig. XIV. The projecting end of piece f' carries a longer transverse pivot f^2 , which runs across between the sides of piece E , in which it is set, and is formed at one end with a project-
10 ing square stem suitable to be engaged with a key. The ends of the links f, f' which are pivoted together form a knuckle-joint, which can move but a short distance below its central or fully-open position because of the stop-
15 piece f^3 , its extreme position being shown in Fig. XVI, in which the piece E' is fully projected and firmly held against lateral pressure unless link f' is turned by the key upon its pivot f^2 and brought to the position shown
20 in Fig. XVII, in which piece E' is withdrawn, so as to allow removal of the sash or its rotation for cleaning or other purposes, as hereinafter described. The bottom rail of the sash is formed of two pieces G, G' , interfolded,
25 as seen in the section appearing in Fig. II. At the corners the stiles and the rails of each sash are interlocked to form a firm joint by means of a series of flaps projecting from the rails and entering corresponding slots in the
30 stiles and fastened by turning over, all of which is clearly shown and will be readily understood from the drawings. Thus the entire sash is formed by interfolding of sheet-metal pieces lengthwise and the interlocking
35 of the same at the corners without the use of screws, bolts, or rivets, which give way under the influence of intense heat. When the rails and stiles have been united for the formation of the sash, the glass-groove e is completely
40 formed, and by removing piece D^2 the glass, which is preferably wire-glass, may be slipped down into the groove and held in place by again inserting piece D^2 , which is in turn held in place by turning over the flaps e' , which
45 appropriately project from the piece E , as seen in Figs. XI and XIX. It will be seen that the interfold between the edges of the pieces D^2 and the edges of the other pieces is entirely formed in the plane of the sash. It
50 therefore results that when the flaps e' are turned back the piece D^2 may be raised out of place without the necessity of moving the window from the frame.

The top sash is formed in all respects similarly to the bottom sash, except that the meeting-rail which is provided with the overlapping flap D^2 is here the bottom rail, its flap being marked H in Fig. XIX.

Automatic closing device.—I have already 55 stated that both the upper and lower sash—the former by reason of its overweight and the latter by reason of its underweight—maintain themselves in their closed positions except when they are otherwise placed and held
60 by a friction device, which I will now de-

scribe. This friction device or friction-shoe is attached approximately centrally to both stiles of both of the sashes. They are all alike, and I will therefore describe but one. It is represented in Figs. XXII to XXIV of 70 the drawings, where, as before, E is the single piece of sheet metal out of which the main part of the stile is formed, and E' the movable or telescopic piece which forms the outer edge of the stile fitting in the runway. K is 75 a friction-shoe set against the outer edge of the stile and supported upon a cross-bar k , which passes through a suitable opening in the side of the piece E' . The inner end of this cross-bar is attached to a long flat metal 80 spring k' , which runs down the interior of the stile nearly centrally and is near the bottom deflected toward the inner edge, against which it finds its point of attachment. The normal pressure of this spring tends to force the shoe 85 K outwardly against the side of the jamb, but not with sufficient pressure to hold the sash in an opened position. In order to increase the pressure of this spring sufficiently to enable it to hold the sash, there is provided a 90 link M , pivoted against the inner edge of the stile at m and having its free end bearing against the extended upper end of the flat spring k' . To this link M is attached a long rod N , which reaches down to near the bottom 95 of the stile, where it is attached to a nut n upon a screw n' , the head of which is seated in a countersunk cap n^2 in the bottom edge of the sash, where it may be turned for adjustment from the outside. By sufficiently tightening 100 this screw the rod N may be drawn so as to cause the link M to press against the spring k' sufficiently to force the shoe K outwardly with such pressure as to maintain the sash in any open position in which it may be placed. 105 Within the cap n^2 at the bottom of the sash a fusible plug P is inserted between the end of the cap and the head of the screw. There is also a coiled spring p interposed between the end of the cap and the nut n . If now by reason 110 of any undue rise of the temperature in the room in which the window is set the fusible plug P is caused to melt, the pressure of the spring p immediately forces the rod N and the link M upward, thus releasing the shoe K 115 from that pressure which maintained it in its open position and allowing it to rise or fall, as the case may be, to its closed position, thus in the case of fire bringing about the immediate closure of all open windows in a 120 building fitted with my invention. It will be observed that the cross-bar k , which connects the shoe K with the spring k' , is not integral throughout, but is broken at one point, with interposition of an axial pivot q . The 125 purpose of this is to allow the sash to be swung upon this pivot when required, so as to obtain access to its outside—as, for instance, for cleaning purposes—without the necessity of removing the entire shoe from its runway. 130

To effect this, the telescopic piece E' is withdrawn into its collapsed position by means of the keys which have been spoken of without releasing or altering the pressure which forces the shoe K out with force enough to hold the sash in position. In this way the sides of the sash are freed from all connection with the jambs, except that resulting from the shoe K. In this connection the entire sash may be partially rotated on the cross-bars k (which are in alinement with each other) as upon a pivot. The sash-chains being attached to the cross-bars do not interfere with this swinging of the sashes.

In Figs. XXV and XXVI, I have shown an alternative form of the automatic pressure device for the shoes of the sash. The shoe, the bar k, and the spring k' remain as heretofore described; but instead of employing the link M and the rod N the necessary pressure upon the spring is obtained by means of a screw R, which engages a threaded aperture near the top of the spring k'. This screw finds its point of resistance in a fusible strip r, which runs from one side of the stile to the other, as seen in Fig. XXVI. By suitably tightening the screw R, for which purpose a hole r' is arranged alongside its head, the requisite pressure may be obtained to operate the shoe, while, as before, any undue rise of temperature melts the fusible strip r, releasing the pressure and allowing the sashes to close themselves.

Having thus described my invention, I claim—

1. A jamb for a non-combustible window-frame consisting of two pieces of sheet metal united by the interfolding of their proximate edges; one of which forms the facing with its runways; while the other forms the rest of the jamb; and a parting-bead, in the shape of an approximately central infold of the last-mentioned piece, to the extremity of which the first-mentioned piece is detachably secured, substantially as described.

2. A jamb for a non-combustible window-frame formed by the union of two pieces of sheet metal; and strengthened by an approximately central vertical infold, extending from one of the pieces, and united at its top to the other piece, substantially as described.

3. A non-combustible window-sash, the meeting-rail of which is formed of three pieces of sheet metal interfolded with each other along their edges, one forming the front, one the back, and one the cover-piece; the interfolds between the edges of the cover-piece and the edges of the other pieces being wholly in the plane of the sash, whereby the cover-piece may be removed for the insertion or removal of the glass without removing the sash from the frame, substantially as described.

4. A non-combustible window-sash, the meeting-rail of which is formed of three pieces

of sheet metal interfolded with each other; the cover-piece being interfolded along its edges with the edges of the other pieces by folds in the plane of the sash, and held in place by flaps projecting from the stiles of the sash, with which it is interlocked by their being turned over, substantially as described.

5. A non-combustible window-sash, the upper rail of which is formed of three pieces of sheet metal which form respectively the front, the back and the cover piece; the lower edges of the front and back pieces being separated from each other for the reception of the glass; the upper edges of the front and back pieces being turned in to form the upper corners of the rail, and then running first down and then up so as to form deep folds in planes parallel with the glass, one on either side thereof; and the cover-piece having its edges turned downwardly so as to be received and held within said folds, substantially as described.

6. A window-sash provided with a telescopic outer edge along the stile fitting the runway; and one or more toggle-joints uniting the telescopic piece to the stile; the link of said toggle-joint which is attached to the stile having the end of its pivot formed to fit a suitable key, and projecting through to the accessible side of the stile, substantially as described.

7. In a window-sash the combination of a stile with a telescopic outer edge fitting the runway; and one or more toggle-joints uniting the telescopic piece to the stile, the link which is attached to the stile having the end of its pivot formed to fit a suitable key, and projecting through to the accessible side of the stile; said toggle being provided with a knuckle-joint, whereby it is prohibited from further motion after the central pivot is depressed slightly below the vertical, substantially as described.

8. In a non-combustible window-sash which by its weight or overweight tends to close itself; a shoe projecting from the side of the stile into the runway; a flat spring upon one end of which said shoe is mounted, the other end being attached to the stile; and means whereby pressure of said spring effective to project the shoe with force enough to maintain the sash in its open position, is obtained by adjustment of a screw, the resistance-point of which is a fusible plug, upon the melting of which said effective pressure is released, substantially as described.

9. In a non-combustible window the combination of a sash which by its weight or overweight tends to close itself; a pivoted rotatable shoe projecting midway from the stile of the sash into the runway; a spring tending to force said shoe into the runway; and means whereby pressure of said spring effective to maintain the sash in its open position is obtained by the adjustment of a screw, the head of which rests within a cap countersunk with

in the bottom rail of the sash; and a fusible plug interposed between the head of the screw and the end of the cap, by the melting of which the pressure of the spring is released, substantially as described.

5 In testimony whereof I have signed my name to this specification, this 31st day of August,

1903, in the presence of two subscribing witnesses.

JOHN W. WATKINS.
